[57] ABSTRACT

A bowling ball is adapted for a selective bowler by producing a specially designed aperture in the ball for the selective bowler's thumb. The aperture is obtained by boring a recess to a depth according to the length of the thumb of the selective bowler and by forming an inwardly tapered first chamber at the inner portion of the recess. A generally cylindrical second chamber also formed in the recess communicates with the first chamber and terminates at the surface of the bowling ball. The diameter of the second chamber substantially corresponds to the maximum diameter of the selective bowler's thumb. The length of the first chamber is such as to accommodate the end portion of the bowler's thumb.

BOWLING BALL

BACKGROUND OF THE INVENTION

1. FIELD OF THE INVENTION

The present invention relates generally to a bowling ball having a specially designed aperture. More particularly, the present invention relates to a bowling ball with a specially designed aperture which is particularly adapted to receive a bowler's thumb.

2. DESCRIPTION OF THE PRIOR ART

The prior art is replete with descriptions of various devices which are theoretically designed to assist a bowler in holding or gripping a bowling ball. Conventionally, these devices are usually in the form of inserts which are to be placed into the thumb hole of a bowling ball so as to provide the bowler with what is generally referred to as a "comfortable fit." When this "comfortable fit" is achieved, a bowler is able to develop and maintain uniform control over the bowling ball and thereby increase his proficiency in the sport.

Such devices, although they do provide the bowler with certain limited benefits, are generally not free from inherent defects. For example, they often lose their intended shape due to use or become separated from their point of placement in the thumb or finger hole or holes of a bowling ball. The result is that they are of little, if any, benefit to a bowler and in fact often have an adverse effect on the user's bowling skills.

SUMMARY OF THE INVENTION

It is an object of the present invention to provide a bowling ball which has a specially designed aperture particularly adapted to receive a thumb of a bowler.

It is another object of the present invention to provide a bowling ball with an aperture as above, such that the shape of the aperture is retained even after extended use.

It is a further object of the present invention to provide a bowling ball with an insert which has a specially designed aperture particularly adapted to receive the thumb of a bowler.

It is a still further object of the present invention to provide a bowling ball with an aperture which substantially corresponds to the diametric profile of the thumb of a selective bowler.

These and other objects of the present invention are accomplished by the means herein described and claimed.

In general, a bowling ball has a specially designed aperture particularly adapted to receive the thumb of a bowler. The aperture is formed by a recess which extends a depth in a bowling ball according to the length of a bowler's thumb. An inwardly tapered first chamber is formed in the inner portion of the recess and a cylindrical second chamber is also formed which communicates with the first chamber and terminates at the surface of the bowling ball. The diameter of the second chamber substantially corresponds to the maximum diameter of a bowler's thumb.

BRIEF DESCRIPTION OF THE DRAWINGS

FIG. 1 is an elevational view of a bowling ball of the present invention, showing an aperture therein broken away and in cross-section which aperture is adapted to receive the thumb of a bowler;

FIG. 2 is a top view taken on line 2-2 of FIG. 1 showing the aperture and finger holes;

FIG. 3 is an isometric illustration of a bowler's thumb, showing the diametric profile of the thumb;

FIG. 4 is an elevational view similar to FIG. 1 showing a slightly modified aperture;

FIG. 5 is an elevational view of a bowling ball showing broken away and in cross-section pilot holes used for making an alternative embodiment of the present invention; and

FIG. 6 is an elevation view similar to FIG. 5 showing 10 the completed form of the alternative embodiment.

DESCRIPTION OF THE EMBODIMENTS

A bowling ball according to the preferred embodiment of the present invention is shown in FIG. 1 and is 15 designated by the numeral 10. The ball, of course, is fashioned from a suitable material which necessarily must be tough and durable. An aperture generally indicated by the numeral 12 is provided in the bowling ball. Since the surfaces of the aperture consist of the 20 bowling ball material, the shape of the aperture will be retained over a long period of time. The aperture has a depth 13 which corresponds substantially to the length of a bowler's thumb and also has a chamber generally indicated by the numeral 14 at its inner or bottom portion. The first or inner chamber 14 is inwardly tapered in that the chamber's diameter generally increases at 25 various points along the length of the aperture as the surface of the ball is approached. A specific configuration of inner chamber 14 is shown in FIG. 1 as containing 30 a series of communicating cylindrical shaped surfaces 16, 18, 20 and 22 with each succeeding outwardly located cylindrical surface having a diameter greater than the diameter of each preceding inwardly located cylindrical surface. Edges 17, 19, 21 and 23 of cylindrical surfaces 16, 18, 20 and 22, respectively, may be sanded or otherwise made smooth as shown in FIG. 4 35 so that a bowler's thumb is not abraded or scratched when the bowler releases the ball.

As seen in FIG. 1, the aperture also has a generally 40 cylindrical second or outer chamber generally indicated by the numeral 24 which communicates with inner chamber 14 and terminates at the surface of 45 bowling ball 10. The outer chamber 24 generally has a diameter which substantially corresponds to the maximum diameter of a bowler's thumb in that it normally is slightly larger to permit facile release of the ball. However, it is not unusual to have the diameter of the 50 second chamber equal to the diameter of a particular thumb as many bowlers desire a tight or snug fit.

FIG. 3 illustrates the diametric profile of a bowler's thumb. The length or the portion of the thumb which is generally received by a bowling ball is generally indicated by numeral 26 and the various diameters which 55 generally increase in size as they approach a bowler's hand are identified by the numerals 28, 30, 32, 34 and 36, respectively.

When adapting a bowling ball to a selective thumb, for example as shown in FIG. 3, a recess is bored in the ball according to the length 26 of a particular thumb. The inner chamber is then formed as by boring and counterboring the inner end of the recess so that the 60 diameters of communicating cylindrical shaped surfaces 16, 18, 20 and 22 substantially correspond to the various generally increasing thumb diameters 28, 30, 32 and 34, respectively, or to the diametric thumb profile. The diameters of various cylindrical shaped surfaces range up to a diameter slightly less than the 65 maximum thumb diameter.

mum diameter of a selective thumb. The outer chamber is then formed as by counterboring the outer portion of the recess with the diameter of cylindrical outer chamber 24 being substantially equal to the maximum diameter of a selective thumb. An elevational view of an aperture thus formed, wherein the various cylindrical surfaces of the inner chamber and the outer chamber may be concentric, is shown in FIG. 2 along with two conventional finger holes 15.

It should be evident to one skilled in the art that the aperture especially adapted for the thumb of a selective bowler can also be formed in a block of material or in an insert generally indicated by the numeral 38 (FIG. 4) and the insert then placed in a correspondingly shaped cavity generally indicated by the numeral 40 provided in the bowling ball. The insert is secured to the ball in any conventional manner such as by the use of epoxy glue.

An alternative embodiment of the invention is shown in FIG. 6 wherein the bowling ball and the aperture are generally indicated by the numeral 110 and 112 respectively. The aperture has a depth 113 which corresponds substantially to and accommodates the length or the portion of a bowler's thumb which is generally received by a bowling ball. The aperture also has an inner and an outer chamber generally indicated by the numerals 114 and 124, respectively. The inner chamber has a generally curvilinear shaped surface which is shown in FIG. 6 as being in the form of a frustum and which may include a conically shaped surface. Generally, the depth and shape of inner chamber 114 is designed such that it accommodates the end portion of a thumb. As in the preferred embodiment, the outer chamber is generally cylindrical, communicates with first chamber 114 and terminates at the surface of bowling ball 110. The diameter of the outer chamber also substantially corresponds to the maximum diameter of a bowler's thumb in that the chamber may be slightly larger than the exact diameter of the selective thumb.

Referring to FIG. 5, the aperture is formed by boring a recess 150 such as a pilot hole and then forming outer chamber 124 as by counterboring. The inner chamber

is then formed as by using a tapered reamer. Of course, it should be evident that the aperture shown in FIG. 6 can also be made in an insert generally indicated by the numeral 138 and then placed and secured in a correspondingly shaped cavity generally indicated by the numeral 140 provided in bowling ball 110.

Although this invention has been described in its preferred form with a certain degree of particularity, it is understood that the present disclosure of a preferred 10 and an alternative form has been made only by way of example and that numerous changes in the details of construction and the combination and arrangement of parts may be resorted to without departing from the spirit and the scope of the invention as hereinafter 15 claimed.

What is claimed is:

1. A bowling ball having at least one finger hole and an aperture which is especially adapted for the thumb of a selective bowler with said aperture having a depth 20 corresponding to the length of a bowler's thumb and including an inwardly tapered first chamber at its inner portion and a cylindrical second chamber communicating with said first chamber and terminating at the surface of the bowling ball, the diameter of said second chamber substantially corresponding to the maximum diameter of the thumb of a selective bowler and the length of said first chamber being such as to accommodate the length of the end portion of a bowler's thumb.

2. A bowling ball having at least one finger hole and an aperture, as set forth in claim 1, wherein said first 30 chamber is a series of communicating, cylindrical shaped surfaces with progressively smaller diameters toward the center of said ball, which surfaces substantially correspond to the diametric profile of the thumb of a selective bowler.

3. A bowling ball as claimed in claim 2, wherein the intersection of said series of communicating, cylindrical shaped surfaces are rounded off to provide a smooth juncture.

4. A bowling ball as claimed in claim 1, wherein said first chamber is shaped as a frustum of a cone.
